JAMES McKECHNIE, OF BARROW-IN-FURNESS, ENGLAND, ASSIGNOR TO VICKERS LIMITED, OF WESTMINSTER, ENGLAND.

FUEL-INJECTION DEVICE FOR INTERNAL-COMBUSTION ENGINES.

1,338,316.

Specification of Letters Patent. Patented Apr. 27, 1920.

Application filed December 1, 1916. Serial No. 134,282.

To all whom it may concern:

Be it known that I, JAMES McKECHNIE, a subject of the King of Great Britain, residing at Naval Construction Works, Bar-
row-in-Furness, in the county of Lancaster, England, have invented certain new and useful Improvements in or Relating to Fuel-Injection Devices for Internal-Combustion Engines, of which the following is a speci-
10 fication.

This invention relates to internal combustion engines of the type in which liquid fuel is injected into the working cylinder by means of a pump and the chief object of the
15 invention is to provide improved means by which the supply of fuel may be controlled so as to give maximum efficiency for varying load on the engine.

According to this invention the fuel is
20 delivered by a pump giving constant fuel pressure (by the aid, for example, of an adjustable relief valve) and the power of the engine is controlled by varying the period of opening of the injection valve, by an ad-
25 justable lever operated by a cam the shape of which is so related to the path given to the end of the lever by the adjustment that for all adjustments and consequent variations in engine power the valve is timed to
30 open at the correct point at which injection should take place. Independent timing means are therefore dispensed with, the cam being formed to give the proper timing for the operation of the valve for all variations
35 in the period of opening. In the construction preferred the control of the injection valve is effected by a valve lever on an eccentrically mounted pivot which varies the clearance between the lever and the cam and
40 at the same time displaces the cam roller over the circumference of the cam in the desired direction to produce, with the cam, the proper timing of the valve opening in con-
junction with the variation in the duration
45 of the opening which determines the power of the engine.

The adjustment of the valve lever cam is preferably effected by lever and link connections to a control wheel which may act
50 through a worm and worm segment. Connections may also pass from the same control to the suction of the fuel pump or pumps so that the output of the pump is simultaneously regulated, for example, by
55 varying the closing of the suction valve.

The pump is of larger capacity than is required by the engine and surplus fuel is discharged through the adjustable relief valve, which is set to give the injection pressure. The control of the suction of the pump al-
60 lows, however, the output of the pump to be regulated as the power of the engine is varied. Excess fuel is always delivered by the pump, so that the pressure to which the relief valve is adjusted is maintained, but
65 the excess over that required by the engine is kept approximately constant, thus assisting the relief valve to maintain a steady pressure. This connection to the fuel pump is particularly desirable for constant speed
70 engines, for example those driving dynamos in which the surplus to be passed by the relief valve would otherwise be greatly increased while running at light loads.

In order that the said invention may be
75 clearly understood and readily carried into effect, the same will be described more fully with reference to the accompanying drawings, in which:—

Figure 1 shows an end elevation of an internal combustion engine fitted with an injection control device according to this invention; and

Fig. 2 shows the front view of part of a multi-cylinder internal combustion engine
85 fitted with the injection control device.

A is the cylinder cover and B the cylinder supported by the columns C. D is the crank shaft from which the cam shaft E is driven by any suitable means, such as spiral wheels
90 f and f' on the intermediate shaft F. G is the fuel oil injection valve which is operated by the cam H on the cam shaft E through the lever J, this lever being mounted on an eccentric fulcrum pin j. This eccentric is
95 controlled by the hand wheel K which partly rotates the rockshaft L through the worm and quadrant k, this motion of the rock-
shaft being transmitted to the eccentric ful-
crum pin j by means of levers j, j' of suitable
ratio and the link j'.

The cam H and the eccentric pin j are so correlated as to obtain the desired timing of opening of the fuel injection valve G at all outputs of the engine, i. e. an approximately
105 constant timing for a constant speed engine, or an advance or retardation for the corresponding increase or reduction of speed in a variable speed engine. The outline of the cam H is so formed with relation to the
110

path given by adjustment of the eccentric fulcrum pin j to the cam roller j^4 at the end of the lever J that, for all clearances between the cam and lever and resulting variation in duration of fuel injection and engine power, the valve is timed to open at the correct point at which injection should take place, without the introduction of special timing mechanism. The eccentric pin j causes adjustment of the roller j^4 both radially to the cam shaft E and circumferentially of the cam H so that, with proper selection of the roller path and formation of the cam surface, the point of opening of the valve G can be determined, in accordance with the requirements of the engine, to give the maximum efficiency at all powers. In constructions hitherto employed, if proper timing of the valve for various powers has been provided for, special timing gear has been used, independent of the cam, but as a rule the proper timing is obtained only for normal running of the engine and the efficiency is allowed to fall for substantial changes in power. The control of the timing by the coöperation of the cam and lever adjustment alone is an essential feature of this invention, in association with the constant pressure pump.

30 The fuel is supplied by the battery of high pressure oil pumps M driven off the end of the crank shaft D by worm gearing d (Fig. 2) or by any other suitable means and the oil is maintained at a high pressure, substantially constant for all powers of the engine, by a relief valve N fitted on the fuel discharge pipe m . This relief valve may be set to act just below the full working pressure required and the pressure of delivery kept constant by controlling the pump in known manner to discharge in excess of the requirements of the engine, the excess being discharged through the relief valve, which thus maintains a steady injection pressure.

45 For very low powers the pressure may be allowed to fall by suitably reducing the output of the pump or by easing back the relief valve.

The control of the pump may be effected

50 through a throttle valve or sleeve O on the suction pipe m' of the fuel oil pump or by varying the period of closing of the suction valve of the pump in a manner already known. The regulation of the pump may be effected simultaneously with the control of the fuel injection valve by suitable link work o , o' and o^2 from the rockshaft L . By thus controlling the pump the relief valve is not called upon to deal with greatly fluctuating quantities of excess fuel and the pressure is kept steady with great facility.

In a multi-cylinder engine such as is shown in Fig. 2, the fuel can be supplied from a single pump or set of pumps delivering the fuel to a common supply or pressure

pipe P from which it is taken off to the separate cylinders B through branch pipes p and isolating valves p' which can cut out any individual cylinder. The rockshaft L actuated by the control wheel K passes along the front of the cylinders and separate link connections are taken off to the injection valve levers of the various cylinders. A multi-cylinder engine can thus be controlled by very simple mechanism which effects the timing and duration of the injection without requiring any special timing mechanism.

The engine shown is of four stroke cycle type (the inlet and exhaust cams being omitted for the sake of clearness) but the invention is equally applicable to two stroke engines.

What I claim and desire to secure by Letters Patent of the United States is:—

1. In an internal combustion engine, a liquid fuel injection valve adapted to inject liquid fuel without the use of compressed air, a liquid fuel pump adapted to compress the fuel to the pressure of injection and to force it through the injection valve on the latter opening, a relief valve at the discharge side of the pump adapted to release the fuel above a predetermined pressure so as to maintain the fuel injection pressure constant, means for regulating the supply of fuel to the pump, a valve lever, a valve cam and means for adjusting the said valve lever both radially and circumferentially of the cam to control the engine power by varying the duration of opening of the valve, the surface of the said cam being so related to the path of adjustment of the end of the valve lever that for all lever adjustments and consequent variations in power of the engine the valve is timed to open at the correct point at which injection should take place, without the use of special timing mechanism, and a control device connected both to the valve lever adjustment and to the fuel admission regulating means of the pump so as to effect simultaneous adjustment of the fuel valve lever and the fuel supply to the pump.

2. In an internal combustion engine, a liquid fuel injection valve adapted to inject liquid fuel without the use of compressed air, a liquid fuel pump connected to the said fuel valve adapted to compress the fuel to the pressure of injection, to maintain such pressure substantially constant and to force the fuel through the injection valve on the latter opening, a valve lever, a valve cam, means for adjusting the said valve lever both radially and circumferentially of the cam to control the engine power by varying the duration of opening of the valve, the surface of the said cam being so related to the path of adjustment of the end of the valve lever that for all lever adjustments and consequent variations in power of the

engine the valve is timed to open at the correct point at which injection should take place, and a connection from the lever adjustment to the suction side of the pump, 5 adapted to regulate the output of the said pump in accordance with the engine power. 3. In a multi-cylinder internal combustion engine, a single liquid fuel pump set adapted to compress the fuel to the pressure 10 sure of injection and to force it into the cylinders, a relief valve at the discharge side of the pump adapted to release the fuel above a predetermined pressure so as to maintain the fuel injection pressure constant, 15 means for regulating the supply of fuel to the pump, a fuel supply pipe from the said pump set to all the engine cylinders, a liquid fuel injection valve for each

cylinder adapted to admit fuel without the use of compressed air, a valve lever and cam device for each cylinder, which device comprises an adjustable valve lever, a valve cam and means for adjusting the said valve lever both radially and circumferentially of the cam to vary the duration of opening of the valve and time its point of opening and a control device connected both to the valve lever adjustment and to the fuel admission regulating means of the pump so as to effect simultaneous adjustment of the fuel valve lever and the fuel supply to the pump. 20 25 30

In testimony whereof, I hereto affix my signature.

JAMES McKECHNIE.
